UNITED STATES PATENT OFFICE.

EUGENE B. ANDES, OF LANCASTER, PENNSYLVANIA, ASSIGNOR, BY MESNE ASSIGNMENTS, TO JOHN J. EDMISTON, OF COLUMBUS, OHIO.

TOY.

Application filed November 16, 1918. Serial No. 262,853.

To all whom it may concern:

Be it known that I, EUGENE B. ANDES, a citizen of the United States, residing at Lancaster, in the county of Lancaster and State of Pennsylvania, have invented new and useful Improvements in Toys, of which the following is a specification.

The present invention relates to improvements in toys and particularly to toys of the character of fire arms. The object of the invention is to provide a toy which will simultaneously discharge a projectile and cause the explosion of a paper cap, for example.

While the invention may be embodied in various forms, it is shown in the accompanying drawing as a toy cannon.

In the accompanying drawings:—

Figure 1 is a vertical sectional view through an embodiment of the invention.

Figure 2 is transverse section substantially on the line 2—2 of Figure 1.

Figure 3 is a similar view on the line 3—3 of Figure 1.

Figure 4 is a horizontal section on the line 4—4 of Figure 1.

Figure 5 is a rear elevation showing the breech open.

Referring to the drawings, the toy comprises a suitable frame or casing 1, which is provided with a forwardly projecting barrel 2, and, as shown, is supported on wheels 3, carried by axles 4 extending through suitable bearings in the main frame. The parts 30 may be of metal or any other suitable material and, as before noted, the form may be changed to represent any other fire arm than a cannon, if desired.

Within the forwardly projecting portion 40 of the frame, above the barrel 2, is formed a magazine chamber which, as shown, is inclined downwardly from its forward to its rear end and connects with the rear end of the barrel 2. A series of projectiles 7 is shown in the magazine, said projectiles being represented as of spherical form, for example, rubber balls.

Normally, the outlet from the magazine to the barrel 2 is closed so that a projectile 7 cannot pass into the barrel by a reciprocating rod 8, which constitutes the means by which the projectiles are successively discharged or ejected from the barrel, as will be hereinafter explained.

This rod is mounted in suitable bearings 55 in the frame 1 and, as shown, a coiled spring 9 is arranged about it between the rear wall of the frame and an abutment 10 secured to the rod. A pin 11 depends from the abutment 10 and is adapted to be 60 operated on by a spiral cam 12 mounted on a shaft 13, having its bearings in the forward and rear walls of the frame 1. The shaft extends rearwardly from the frame or housing and is provided with a detachable 65 crank 14, by means of which it may be rotated. It will be seen that at each rotation of the shaft 13 by the crank 14, the spiral cam 12 will operate to move the rod 8 rearwardly, compressing the spring 9, and when the spiral cam 12 passes from engagement with the pin 11 the rod will be forcibly driven 70 forward and caused to eject the projectile 7, which has been previously positioned in front thereof, from the barrel 2.

To insure that only a single projectile can pass from the magazine to the barrel when the firing rod 8 is withdrawn, a spring finger 16 is provided. This projects slightly into the barrel so that it will frictionally engage 80 the projectile 7 as it drops from the magazine and thus retain it in position to prevent a second ball or projectile passing through the outlet from the magazine. As shown, the finger 16 is one end of a spring wire 85 which is coiled at an intermediate point in its length about a stud 17 and has its forward end bent upwardly as at 18 through an aperture in the bottom wall of the magazine tube near the inlet end thereof. The bent 90 section 18 thus acts as a stop to prevent the projectiles being withdrawn or accidentally escaping from the magazine, although it will readily yield to permit the balls to be inserted.

As shown, a flexible strip, for example, paper, provided with a series of explosive caps 21, is coiled about a supporting pin or rod 22 mounted in lugs near the upper end of the frame or casing 1, and said strip passes downward between the shaft 13 and a friction feed roll 23 across an anvil or firing block 24, with which is adapted to co-operate a firing hammer 25. As shown, the feed roll 23 is loosely mounted on a stud projecting laterally from an arm 26, which is pivotally supported at its upper end on the same pin or rod that serves to support the

cap strip, and the shaft 13 is provided adjacent said feed roll with a short eccentric section having formed thereon a series of ribs 27, extending partially about the shaft 5 and adapted to cooperate with the feed roll 23 to intermittently feed the strip 20 as the shaft is rotated. A spring 28 acts to hold the roll 23 in engagement with the strip and press the same against the ribs 27 so that the 10 feeding action may be effected.

The hammer 25 is shown as provided with a stem 30 which is mounted on the pin 22 between the members of the arm 26, and a spring 31 acts to constantly draw the head 15 of said hammer toward the anvil 24. As the shaft 13 is turned, a cam 32 thereon will engage the arm of the firing hammer and move the same against the action of the spring 31 away from the anvil. The cam 32 20 and spiral cam 12 are so related that the firing hammer will be released by the cam practically simultaneously with the passing of the spiral cam 12 from engagement with the pin 11, so that as the firing rod 8 is projected forward by the spring 9 and the projectile 7 discharged from the barrel the hammer will strike the cap 21 which has been positioned against the face of the anvil 24, thus producing a simultaneous explosion and 25 discharge of a projectile.

To permit ready insertion of a strip of caps or correct any disarrangement of the feeding device, the rear end of the casing or housing 1 is provided with a swinging 30 breech 35.

The operation of the toy will, it is thought, be evident from the foregoing description in connection with the drawing.

It will be seen that the device is of very 40 simple construction, including a minimum number of parts which will not be readily disarranged or broken and that the operation is a close imitation of the actual firing of a cannon or other fire arm, the explosions 45 occurring simultaneously with the ejecting of the projectiles from the barrel.

Having thus described my invention, what is claimed is:—

1. A toy of the character described, comprising a frame including a barrel, a spring 50 pressed rod adapted to discharge a projectile from the barrel, a cam rotatable about an axis extending parallel to the length of said rod and cooperating therewith to move it in opposition to its spring, and a crank at the rear of the frame for rotating said cam.

2. A toy of the character described, comprising a frame including a barrel, a reciprocating rod mounted in the frame and extending into the rear end of the barrel, a shaft mounted in bearings in the frame and extending parallel to said rod, a spiral cam 60 on said shaft, a spring acting to force the rod forward into the barrel, and a projec-

tion on the rod extending into the path of said cam, whereby as the shaft is turned the rod will be moved rearward in opposition to the spring and then released.

3. A toy of the character described, comprising a frame having the form of a cannon with a forwardly projecting barrel and a movable breech end, a reciprocating rod mounted in the frame in alignment with and adapted to extend into the rear end of the barrel, a coiled spring acting to force the rod into the barrel to eject a projectile therefrom, a shaft mounted in bearings in the frame, a crank on said shaft outside of the frame, means actuated by the shaft for 70 moving the rod against the action of its spring and then releasing it, an anvil or firing block within the frame adapted to have an explosive cap positioned against its face, a firing hammer cooperating with the anvil, a spring acting to force the hammer against the anvil, and a cam on the shaft for moving the hammer in opposition to said spring.

4. In a toy of the character described, the combination of a frame including a barrel, a spring actuated rod adapted to eject a projectile from the barrel, means for supporting a strip of explosive caps in the frame, means for feeding said strip, means 90 for firing the caps successively as the rod is moved to eject a projectile from the barrel, and a single shaft adapted to control movement of said rod, strip feeding means and explosive devices.

5. In a toy of the character described, the combination of a frame including a barrel, a spring actuated rod adapted to eject a projectile from the barrel, a shaft mounted in the frame and provided with means controlling rearward movement of said rod, means for supporting a strip of explosive caps, a spring pressed roll within the frame adapted to press said strip into contact with a portion of the shaft at each rotation of the latter to feed said strip, an anvil against which the caps are successively moved by said feeding device, a pivotally mounted hammer adapted to co-operate with the anvil to explode the caps, a cam on the shaft 105 for moving the hammer from the anvil as the projectile ejecting rod is withdrawn from the barrel, and a spring for moving the hammer against the anvil when it is released by said cam.

6. A toy of the character described comprising a frame in the form of a cannon having a barrel and a movable breech closure, a spring impelled rod within the frame in alignment with the barrel adapted to propel projectiles therethrough, a support for a strip of explosive caps within the rear end of the frame so as to be exposed when the breech closure is in open position, means within the frame for exploding the caps in- 110 120 125 130

cluding a pivotally mounted hammer, a shaft extending parallel to the projectile expelling rod within the frame and beyond the rear end of the latter, a crank secured on the rear end of said shaft, and means on the shaft within the frame for controlling movement of the projectile expelling rod and the cap exploding hammer and for causing step by step movement of the strip of caps to successively bring the caps into position to be struck by the hammer.

In testimony whereof I have hereunto set my hand.

EUGENE B. ANDES.
